UNITED STATES PATENT OFFICE.

JOHN MARRIOTT DRAPER, OF MANCHESTER, ENGLAND.

FINE COAL AND ORE SEPARATOR.

1,151,448.

Specification of Letters Patent. Patented Aug. 24, 1915.

Application filed April 4, 1914. Serial No. 829,581.

To all whom it may concern:

Be it known that I, JOHN MARRIOTT DRAPER, a citizen of the United States of America, residing at Curzon Buildings, 38 5 King street west, Manchester, England, have invented new and useful Improvements in Fine Coal and Ore Separators, of which the following is a specification.

This invention relates to an improved construction of apparatus for separating fine 10 from coarse materials such as is employed in the treatment of coal and ores which are subjected to the pulsating action of a liquid produced through the perforated bottom of a separator box to one end of which such material is supplied, and along which bottom it travels and is delivered at the 15 opposite end of the box, the water removing the fine portions therefrom in its passage 20 through the perforations.

The movement of the water through the perforated bottom of the separator box will be produced in the known manner either by a plunger acting on a portion of the 25 surface of the liquid or by imparting a jiggling motion to the separator box in the liquid in which same is immersed.

The fine material removed by the suction 30 action of the water in its downward passage through the perforated bottom of the separator box will consist of an admixture of fine dirt and finely divided particles of the material being treated, which latter it is the 35 object of the present invention to separate and to recover.

A suitable manner of carrying my invention 40 into effect is illustrated in the accompanying drawings as applied to a coal separator or washer, in which a jiggling movement is imparted to the box in which the material is treated.

In these drawings Figure 1 is a longitudinal section of the improved separator or washer. Fig. 2 a plan view, and Fig. 3 a 45 transverse section thereof. Figs. 4 and 5 are respectively a longitudinal section and plan view of the separator box, drawn to a larger scale.

In these drawings A is the tank in the 50 water contained in which the separator box or pan B is in the usual manner caused to reciprocate by connecting rods actuated from a driving shaft operated from any suitable source of power, and the water passing through the perforated bottom H of which acting upon the material fed to one

end of the box as it passes under gate I and travels along to the point of delivery over the sill O at the front end of such box, causes same to separate by gravity according 60 to density.

The bottom H of box B is preferably inclined toward the point of delivery as shown in order to facilitate the travel of the material over same.

Beneath the primary perforated bottom H the box B is formed with a secondary perforated bottom J with an intervening space K constituting a chamber on the floor of which a layer of stone chips is spread to a 70 depth of 2 or 3 inches, but with sufficient clearance above the top to enable the chips to rise and fall under the action of the water in its passage through the secondary bottom J and exercise a controlling valvular action 75 over the perforations therein.

The perforations of the secondary bottom J will be larger than those of the primary bottom H.

As the primary bottom H of box B is 80 preferably inclined, while the secondary bottom J has to occupy a horizontal position, in order that too great a depth may not have to be allowed over the chips at the inner end, such secondary bottom J may 85 be formed on two or more levels or planes constituting steps as shown.

On the downward stroke of the box or pan B water enters first through the perforations of secondary bottom J and passing up through the stone layer and thence through the finer perforations of the primary bottom H, effects the separation of the material contained in the box or pan 95 according to the relative specific gravities thereof.

On the upward stroke a strong suction action will take place, which first operating through the large lower perforations of the secondary bottom J has the result of drawing the stone chips over such perforations so as to practically close same.

This suction action also obtains through the smaller perforations of the primary bottom H, whereby part of the fine material is 105 drawn through into the intermediate chamber K between bottoms H and J. Owing to the earlier closing of the perforations in the secondary bottom J the downward suction action experiences a check between the 110 two bottoms H and J, whereby the heavier particles only of the fines are allowed to set-

tle or pass downward through bottom J into the tank below, the lighter material remaining in suspension between the two bottoms and passing along toward the delivery end of box B until on reaching a point where the heavier particles have already passed out, such lighter particles gradually settle down and in turn pass out through the secondary bottom J into the tank below.

Practically all the heavy fines will pass down through the first 18 inches of the length of the box B, so that if this is prevented from remixing with the lighter fines which pass down through the remaining portion of the length, it can be passed out of the machine separately. The fine dirt being thus largely removed as the material passes along the separator box B forward, a point is reached where the product passing through the secondary bottom is wholly or mainly light fines or coal, which is caused to pass to a separate chute and can be conveyed back to the box B for rewashing if desired or forwarded direct to washed coal delivery. For this purpose the feed end of the box B is situated over the chute 1 formed in tank A and which delivers into the elevator arranged on the left hand side of the machine (Fig. 3), and which disposes of the heavy fines passing out through such end of the secondary bottom J, while the remaining or forward portion of bottom J is situated over a chute 2, formed in said tank A and which receives the light fines or coal passing through said bottom and delivers it to an elevator on the right hand side of the machine (Fig. 3), which either delivers it from the machine or raises it to a chute 5 which conveys it back to box B for rewashing if desired.

In order to determine the point of separation of delivery of the heavy and the light fines into their respective chutes 1 and 2 an adjustable gate or deflector E is pivoted on a fixed division board M and through rod N and a crank connection can be adjusted so as to divert the material passing through the bottom of box B to one side or other, and consequently determine accurately the point 50 where the delivery to chute 2 is to start.

When the material to be treated contains only a small proportion of fines which are liable to be removed through the perforated bottom of box B, but from which it is desirable to recover a valuable portion, only a portion of the width of such box need be fitted with a secondary perforated bottom, the remaining portion having a single or primary perforated bottom only. Such a 60 construction is represented in the plan shown in Fig. 5 of the drawings, where the box B is divided by a longitudinal partition X, the material to be treated being delivered to the compartment Y of the box on one side 65 of such partition, which is provided with

the usual or primary perforated bottom only, the whole of the fines passing through which single bottom are conveyed back and delivered to the compartment Z on the other side of partition X, which is provided with 70 both a primary and a secondary perforated bottom which effect the separation of the heavy and the lighter fines in the manner hereinbefore described.

In order to effect the supply of stone 75 chips to the chamber K between the primary and secondary perforated bottoms H and J of box B, pockets G are provided preferably at the opposite ends of the box as shown, and which are open at top and at bottom open into such chamber K, so that a suitable supply of chips dropped into such pockets will under the jiggling action of the box in the water be immediately distributed in a layer of uniform depth over the perforations of the secondary bottom J on which they rest. A fresh amount of chips 80 may be introduced through such pockets from time to time to replace the loss occasioned by abrasion and a rod introduced into 85 one of such pockets will enable the desired depth of the layer to be readily gaged.

The primary perforated bottom H of box B terminates before the sill O so as to leave an opening P, beneath which a cradle C is pivoted, and is connected by an arm R to a weighted rod S. The cradle C is directed toward the feed end of the machine, and the heavy material which passes through opening P accumulates thereon until overcoming 95 the weight acting on rod S, it will cause cradle C to fall and be discharged toward the feed end of the machine into chute 3, the bottom of which delivers to the same elevator as that with which the chute 1 of the 100 heavy fines communicates, so that the same elevator serves to deliver both the heavy fines and the heavy separated material together from the machine.

The light separated material constituting 110 the upper stratum of the material at the delivery end of box B, as it accumulates surrounds the upper edge of sill O and falls into chute 4 communicating with the elevator occupying the central portion of the machine, and by which it is delivered from the 115 machine.

The water passing with the separated coal through chute 4 passes from the central elevator casing in the direction shown by the 120 arrows to trough F which conveys it back to tank A at a point below the separator box B, thus establishing the necessary circulation of the water and maintaining the level of the liquid in said tank.

It has already been proposed to employ a pivoted part constituting the bottom of the separator box or acting in conjunction therewith and allowing of the discharge of heavy materials either in the direction of the de- 130

livery end of such box or to one side thereof, and I therefore lay no claim to the employment of a pivoted part discharging in either of such directions.

5. What I claim as my invention, and desire to secure by Letters Patent, is—

1. A jig box having an elongated inclined perforated bottom, a perforated bed-supporting bottom beneath the same and in proximity thereto, comprising sections longitudinally arranged in stepped relation, the perforations of the first mentioned bottom being smaller than those of the bed supporting bottom, the first bottom being adapted 10 to initially receive the material to be separated, and means for forcing an intermittent current of fluid through the bottoms.

2. A jig box having an elongated inclined perforated bottom, a perforated bed-supporting bottom beneath the same and in 15

proximity thereto, comprising sections longitudinally arranged in stepped relation, the perforations of the first mentioned bottom being smaller than those of the bed supporting bottom, the first bottom being adapted to initially receive the material to be separated, and means for forcing an intermittent current of fluid through the bottoms, each step portion of the bed-supporting bottom being provided with an inlet conduit for bed-material located outside the area of the first bottoms. 25

30 In testimony whereof I have signed my name to this specification in the presence of two subscribing witnesses.

JOHN MARRIOTT DRAPER.
